UNITED STATES PATENT OFFICE.

FRANZ KELLNER, OF BARMEN, GERMANY.

BRAIDING OR LACING MACHINE.

1,340,487.

Specification of Letters Patent. Patented May 18, 1920.

Application filed April 14, 1917. Serial No. 162,209.

To all whom it may concern:

Be it known that I, FRANZ KELLNER, a subject of the Emperor of Germany, and residing at Barmen, Germany, have invented 5 a new and useful Improvement in Braiding or Lacing Machines, of which the following is a full and clear specification.

My invention refers to that class of braiding machines having one bobbin per plate 10 and it has for its object a new device for temporarily locking the bobbin at each intersection of the bobbin track said device comprising a spring controlled locking lever which is governed by a disk which being 15 rocked by the pattern mechanism ejects the bobbin into the track pushing it either to the left or the right.

With these and other arrangements in view my invention is fully shown on the 20 accompanying drawings on which—

Figure 1 shows a plan view of a portion of a braiding machine having one bobbin per plate and, fitted with my improvement, said view having parts broken away,

25 Fig. 2 is a vertical section along line A—A and

Fig. 3 a similar section along line B—B of Fig. 1

Figs. 4 and 5 are vertical sections along 30 lines C—C and D—D of Fig. 2 and Fig. 3 respectively.

Like letters of reference indicate like parts in the drawings.

In the said drawings the reference numerals *a* indicate the plates which together with the top plate *b* of the machine form the braiding track *c* for the bobbins. Below said plates *a* there are mounted in a known manner the bobbin drivers *e* which revolve 40 in direction of the arrow. At each intersection of the track the plate *b* is cut away in the moving direction of the bobbins in order to lock the same after they have passed the crossing place.

45 On the bottom plate *f* of the machine is mounted a bracket *g*, in which is journaled by means of a fulcrum *h'* a lever *h*, controlled by a spring *i*, which holds it elevated said lever assuming a radial direction and 50 having its free end forked in order to constitute an entrance for the bobbin so that the same approaching from left or right by means of said forked lever head will be brought out of engagement with the bobbin 55 drivers and locked within the broadened track, said locking takes place as soon as the

said lever *h* is in the lifted, that is, the original position.

For again ejecting the bobbin into the track I prefer to employ a controlling disk 60 *l* which is mounted below the top plate *b* of the machine and operates upon the bobbin flange or collar *m* by means of two horns *m'* *m*². Said disk forms part of a vertical bolt *n* which is guided in the bracket *g* and bottom plate *f* and passes freely through a hole of lever *h* and is fitted at its end with a lever arm *n'*, leading to the pattern mechanism and rocked temporarily by the same. This motion is transmitted to the disk *l* 70 which by means of its horns *m'*, *m*² propels the bobbin either to the left or the right ejecting it thereby into the track, where it is seized by the drivers and taken around to proceed in braiding. Upon the bottom 75 face of the controlling disk *l* is mounted an angular offset *o*, with which engages a roller *q* forming part of lever *h*, said engagement will be a close one due to the action of the spring *i*. From this will be clear that the 80 disk *l* in rocking to the left or right will turn down the lever *h*, its forked head releasing thus the bobbin whereupon the same is ejected into the track. This section of operating the lever *h* will be best understood 85 from Figs. 4 and 5.

What I claim is:

1. In a braiding machine having one bobbin per plate the combination of a spring controlled lever, said lever forming an entrance for the bobbin, means to operate said lever and a rocking disk, said disk having horns for ejecting the bobbins and means to rock the disk as described and for the purpose set forth. 90

2. In a braiding machine having one bobbin per plate the combination of a spring controlled lever forming an entrance for locking the bobbin, a roller mounted on said lever a rocking disk ejecting the bobbin, 100 means to oscillate said disk, an angular offset projecting from said disk and co-operating with said roller as described and for the purpose set forth.

In testimony whereof, I have signed my 105 name to this specification in the presence of two subscribing witnesses.

FRANZ KELLNER.
